UNITED STATES PATENT OFFICE.

EDWARD LEGER, OF CHICAGO, ILLINOIS.

DESIGN FOR A GARMENT-RACK.

SPECIFICATION forming part of Design No. 28,770, dated May 31, 1898.

Application filed March 21, 1898. Serial No. 674,683. Term of patent 14 years.

To all whom it may concern:

Be it known that I, EDWARD LEGER, of Chicago, county of Cook, and State of Illinois, have invented and produced a new and original Design for Garment-Racks, of which the following is a specification, reference being had to the accompanying drawing, forming a part thereof.

The figure is a perspective view of my newly invented design.

The leading features of my design consist in the standard A, the ornamental base B, the top or cap C, and the ring D.

The base is supported above the floor by the integral feet a a a a, widely diverging. The upper side of the base and feet are provided with an ornamental surface consisting, preferably, of embossed or raised ornamentations.

The large ring D surrounds the standard some distance from the upper end, as shown, 20 and is connected therewith by the suspension inclined rods b b b and the horizontal rods d d d.

My design therefore consists, essentially, of the standard A, the base B, the top C, and the ring D, as shown in the drawing.

What I claim is—

The design for a garment-rack, substantially as herein shown and described.

EDWARD LEGER.
